UNITED STATES PATENT OFFICE.

JACOB M. JOHNSON, OF MADISON, WISCONSIN.

PIPE.

1,002,405.

Specification of Letters Patent. Patented Sept. 5, 1911.

Application filed July 11, 1910. Serial No. 571,317.

To all whom it may concern:

Be it known that I, JACOB M. JOHNSON, a citizen of the United States, and a resident of Madison, in the county of Dane and State of Wisconsin, have invented certain new and useful Improvements in Pipes; and I do hereby declare that the following is a full, clear, and exact description thereof, reference being had to the accompanying drawings, and to the letters of reference marked thereon, which form a part of this specification.

This invention relates to improvements in tobacco pipes and consists of the matters hereinafter described and more particularly pointed out in the appended claims.

The object of the invention is to supply a tobacco pipe having the simple lines of the usual pipe and provided with means located intermediate the mouth-piece and the pipe bowl to prevent particles of tobacco from being drawn from the bowl into the mouth and saliva from reaching the pipe bowl.

Other advantages of the pipe will appear as I proceed with my specification.

In the drawings:—Figure 1 is a perspective view of a tobacco pipe provided with my improvements. Fig. 2 is a central longitudinal, vertical section through the pipe stem on an enlarged scale. Fig. 3 is a cross-section through Fig. 2 on the line 3—3 thereof. Fig. 4 is a cross section similar to Fig. 3 showing the parts in that position which they occupy when the mouth-piece is about to be withdrawn from the stem. Fig. 5 is a cross-section through Fig. 2 on the line 5—5 thereof. Fig. 6 is a cross-section through Fig. 2 on the line 6—6 thereof. Fig. 7 is a perspective view of the inner end of the mouth-piece.

In the drawings 10 indicates the bowl of the pipe; 11, the stem, preferably made integral therewith; and 12, is the mouth-piece made of amber or any other suitable material.

11^a and 12^a are the usual apertures, respectively, through the stem and the mouth-piece, through which the smoke is drawn.

13 is an intermediate member between the stem proper and the mouth-piece proper in which are located the parts comprising my improvements. Said intermediate member consists of a cylindric tube, preferably of metal of the diameter of the stem and closed at the rear end by a wall 13^a which abuts

against the end of said stem and forms a smooth unbroken surface at the junction of the stem with the cylinder 13.

14 is an apertured stud projecting on both sides of the wall 13^a and having a screw-threaded rear end 14^a which engages within a threaded recess formed in the end of the stem. The front end 14^b of said stud projects within the cylinder 13. The aperture 14^c through said stud coincides with the aperture 11^a of the stem 11 and is in line with the aperture 12^a of the mouth-piece.

To the rear end of the mouth-piece 12 is secured a semi-cylindric shell 15 which is adapted to fit within the cylinder 13. Said shell 15 is preferably made integral with a plug 15^a adapted to be embraced by the front end of the cylinder 13 and having on its forward side a threaded stud 15^b which is screwed into a threaded aperture in the rear end of the mouth-piece 12. The plug 15^a is provided with an aperture 15^c.

16 is a short tube projecting within the cylinder 13 and preferably made integral with the plug 15^a. It is located in line with the aperture 15^c of said plug and is closed at its rear end by a baffle plate 16^a. 16^b is a notch or opening cut in the side and bottom walls of said tube forward of the baffle plate. It will thus be apparent that anything drawn into the aperture of the mouth-piece must pass about the lower edge of the baffle plate 16^a before it may enter the aperture 15^c.

The rear end of the shell 15 is closed by an end wall 15^x provided on its upper edge with a half-round notch 15^y which is adapted to receive the front end 14^b of the stud 14 when the parts are assembled. One edge of the shell 15 has a notch 17, preferably next to the plug 15^a, which is adapted to be engaged by a pin or lug 17^a projecting radially inward from the cylinder 13 to lock the shell 15 within the cylinder 13. A cylinder 18 of absorbent material is preferably located in the shell 15, with one end abutting against the plug 15^a and the other against the end wall 15^x of said shell. This arrangement insures the withdrawal of the absorbent cylinder with the shell.

From this construction it is apparent that any particles of tobacco that may be drawn through the aperture 11^a of the stem into the space within the cylinder 13 will impinge against the baffle plate 16^a and drop into the shell 15, or in the case of the use of the

absorbent cylinder, into said cylinder. It will thus be prevented from entering the aperture of the mouth-piece. It will also be apparent that any saliva that runs from the 5 mouth-piece through the tube 16 will be caught in said shell or by the absorbent cylinder.

The parts are readily taken apart for the purpose of cleaning. This is done by simply 10 giving the mouth-piece a part turn, to rotate it from the position illustrated in Fig. 3 where the pin 17 is engaged with the notch 17 to the position illustrated in Fig. 4 where the shell 15 has been rotated beyond the 15 locking position, whereupon the mouth-piece may be withdrawn and with it the semi-cylindric member 15 containing the absorbent cylinder. The parts may be thoroughly cleaned, and, if desired, a new absorbent 20 cylinder placed within the shell 15.

I claim as my invention:—

1. In a pipe, in combination with the stem and the mouth-piece, a tubular member closed at its rear end by a wall, said wall 25 being provided with an apertured stud having a rear end engaged within an aperture in said stem and a front end projecting within said tubular member, a plug secured to said mouth-piece adapted to be embraced by the 30 forward end of said tubular member, a small tube made integral with said plug opening into the aperture of said mouth-piece and closed at its rear end, said tube having a slot in its lower side forward of 35 said rear closed end, and an open shell made integral with said plug adapted to fit within said tubular member, said shell having an end wall provided with a notch adapted to receive the forward end of said stud.

40 2. In a pipe, in combination with the stem and the mouth-piece, a tubular member closed at its rear end by a wall, said wall being provided with an apertured stud having a rear end screw-threaded into said stem 45 and a front end projecting within said tubular member, a plug secured to said mouth-piece adapted to be embraced by the forward end of said tubular member, a small tube made integral with said plug opening 50 into the aperture of said mouth-piece and closed at its rear end, said tube having a slot in its lower side forward of said rear closed end, an open shell made integral with said plug adapted to fit within said tubular member, said shell having an end wall provided

with a notch adapted to receive the forward end of said stud, said shell being provided on one of its longitudinal edges with a second notch, and a pin or lug made rigid with said tubular member adapted to engage 60 said notch to lock the parts in assembled relation.

3. In a pipe, in combination with the stem and the mouth-piece, a tubular member closed at its rear end by a wall, said wall 65 being provided with an apertured stud having a rear end screw-threaded into said stem and a front end projecting within said tubular member, a plug secured to said mouth-piece adapted to be embraced by the 70 forward end of said tubular member, a small tube made integral with said plug opening into the aperture of said mouth-piece and closed at its rear end, said tube having a slot in its lower side forward of 75 said rear closed end, an open shell made integral with said plug adapted to fit within said tubular member, said shell having an end wall provided with a notch adapted to receive the forward end of said stud, and means for 80 locking the parts in assembled relation.

4. In a pipe, in combination with the stem and the mouth-piece, a tubular member closed at its rear end by a wall, said wall 85 being provided with an apertured stud having a rear end screw-threaded into said stem and a front end projecting within said tubular member, a plug secured to said mouth-piece adapted to be embraced by the 90 forward end of said tubular member, a small tube made integral with said plug opening into the aperture of said mouth-piece and closed at its rear end, said tube having a slot in its lower side forward of 95 said rear closed end, an open shell made integral with said plug adapted to fit within said tubular member, said shell having an end wall provided with a notch adapted to receive the forward end of said stud, an absorbent member located in said shell, and means for 100 locking the parts in assembled relation.

In testimony, that I, claim the foregoing as my invention I affix my signature in the presence of two witnesses, this 2nd day of July A. D. 1910.

JACOB M. JOHNSON.
